UNITED STATES PATENT OFFICE.

EARL W. MYERS, OF NEW YORK, N. Y.

DESIGN FOR A HANDLE FOR PLIERS OR SIMILAR GRIPPING-SURFACES.

57,252.

Specification for Design.

Patented Mar. 8, 1921.

Application filed June 8, 1920. Serial No. 387,467. Term of patent 14 years.

To all whom it may concern:

Be it known that I, EARL W. MYERS, a citizen of the United States, residing in New York city, in the county of New York and State of New York, have invented a new, original, and ornamental Design for a Handle for Pliers or Similar Gripping-Surfaces, of which the following is a specification, reference being had to the accompanying drawing, forming part thereof.

Figure 1 is a plan view of a pliers embodying my new design;

Fig. 2 is a side elevation thereof, and Fig. 3 is an enlarged transverse sectional view taken on line 3—3 of Fig. 1.

No claim to novelty is made on the jaws of the pliers or the pivoting thereof, these parts being shown merely for the purpose of clearly illustrating one application of the invention.

I claim:

The ornamental design for a handle for pliers or similar gripping surfaces, as shown.

EARL W. MYERS.
